(57) **CLAIM**

The ornamental design for a hairdryer diffuser head, as shown and described.

DESCRIPTION

FIG. 1 is a front perspective view of the hairdryer diffuser head showing our new design;

FIG. 2 is a front view thereof;

FIG. 3 is a back view thereof;

FIG. 4 is a left view thereof where the right view is a mirror image;

FIG. 5 is a top view thereof where the bottom view is a mirror image;

FIG. 6 is a back perspective view thereof; and,

FIG. 7 is another perspective view thereof shown in condition of use with environment.

The portions of FIG. 7 drawn in broken lines show environmental structure only and form no part of the claimed design.

1 Claim, 7 Drawing Sheets
